UNITED STATES PATENT OFFICE.

FERDINÁND DEÁK, OF TOLEDO, OHIO.

WRENCH.

1,109,282.

Specification of Letters Patent.

Patented Sept. 1, 1914.

Application filed February 6, 1914. Serial No. 816,962.

To all whom it may concern:

Be it known that I, FERDINÁND DEÁK, a subject of the King of Hungary, residing at Toledo, in the county of Lucas and State 5 of Ohio, have invented certain new and useful Improvements in Wrenches, of which the following is a specification.

This invention relates to improvements in self-locking quick action wrenches.

10 An object of the invention is the provision of a hand wrench having a movable jaw so mounted thereon as to be readily moved into engagement with the work, and upon such engagement therewith to be firmly locked in the gripping position automatically.

15 A further object is to provide a freely movable wrench jaw with two members pivoted thereto coöperating in locking said jaw into engaged position with the work.

20 A still further object is to provide a wrench which is easily and inexpensively manufactured and at the same time incorporates added efficiency in its rapid adjustment and automatic locking features, and which shall be capable of grasping all kinds of work surfaces, such as tubes and pipes, without slipping.

25 With these objects in view and others that 30 will appear as the nature of the invention is better understood, the same consists in the novel combination and arrangement of parts hereinafter fully described, illustrated in the accompanying drawings, and pointed 35 out in the appended claims.

30 In the drawings forming a part of this application and in which like designating characters refer to corresponding parts throughout the several views:—Figure 1 is 40 a side elevation of the wrench locked in engagement with a bolt nut. Fig. 2 is a front view thereof. Fig. 3 is a detail view similar to Fig. 1 partly in central vertical section and with the movable jaw disengaged from 45 the work. Fig. 4 is a perspective view of the pivoted jaw-face plate and the pivot pin therefor, and, Fig. 5 is a perspective view of the movable jaw detached, with its movable rack partially broken away.

50 Referring more in detail to the drawings, the main shank is illustrated composed of the side bars 10 and 11 spaced apart for providing the intermediate slot 12 and having a fixed jaw 13, and a handle member 14 55 at its opposite end. It is noted that substantially the entire structure is preferably

formed of metal while the handle portions 15 may be formed of wood and secured upon opposite sides of the intermediate metal handle member 14.

60 The bar 11 is provided with ratchet teeth 16 for the purpose hereinafter described while a movable rack member 16^a is slidably positioned within said longitudinal slot 12 and adapted for reciprocation in and out of the longitudinal bore or socket 17 within the handle by means of the pinion 18 meshing with the said rack teeth and journaled upon a shaft 19 positioned transversely through the bars of the shank.

65 The movable jaw 20 having a central opening 21 therethrough is slidably-mounted upon said shank, being secured loosely by means of a pin 22 to the upper end of the rack 16^a, and whereby as will be apparent, a movement of said rack by means of the pinion 18 carries said movable jaw into and out of engagement with the work to be operated upon.

70 The present construction of movable jaw provides a jaw-face plate 23 of substantially two-thirds the area of the engaging face of said jaw and pivoted thereto by means of terminal downwardly-extending lugs 24 pierced in alinement for the reception of the 75 pivot pin 25 extending through the same as well as through a transverse perforation 26 of said jaw.

75 A dog 27 is provided with upwardly-extending substantially central lugs 28 by means of which the same is pivoted partially within a socket 29 of the movable jaw and upon the transverse pin 30 positioned through the same. Said dog is normally held with its pointed end 31 out of engagement with the rack by means of the expansion spring 32 bearing thereagainst and seating in a socket 33 of the movable jaw, while also, the opposite end of the dog is normally in contact with one end of a pin 34 projecting through the perforation 35 of the working face of the movable jaw and bearing at its other end beneath the said pivoted face plate 23 for normally holding the latter elevated as illustrated in Fig. 3, 100 and thereby positioned at an angle to the remaining face portion 36 of the movable jaw.

105 For actively engaging the wrench with the work such as the bolt nut 37 herein illustrated, it is only necessary to slide the movable jaw 20 upwardly on the shank with the

hand and assisted by rotating the pinion 18 with the finger or thumb of the operator, and whereupon an engagement of the pivoted face 23 with the work results in depressing the outer end of the dog and thereby bringing the pointed tooth 31 thereof in engagement with the adjacent tooth of the rack 16^a, and whereupon as illustrated in Fig. 1, the automatic locking of the movable jaw to the work is effected. It will therefore be seen that a sliding movement of the jaw into engagement with the work may be rapidly effected as well as the automatic locking of the movable jaw to the shank teeth 16.

It is evident that the wrench may be disengaged by laterally sliding the same from the work or by a reverse movement of the wrench resulting in allowing the spring 32 to return to its normal position, releasing the dog tooth 31 from the shank rack 16, whereupon the pinion 18 may be utilized for further shifting the movable jaw away from the work.

While the forms of the invention herein shown and described are what are believed to be preferable embodiments thereof, it is nevertheless to be understood that minor changes may be made in the form, proportion and details of construction, without departing from the spirit and scope of the invention as set forth in the appended claims.

Having thus fully described the invention, what I claim as new is:

1. In a wrench, a slidable jaw having a portion of its engaging face cut-away, a face plate adapted for alinement with the face portion of the jaw and pivotally mounted on the latter, said jaw having a socket, a dog pivoted within said socket to said movable jaw and a pin extending through an opening in the slidable jaw and adapted to engage said face plate and dog, said dog having a pointed end adapted for automatic engagement with a fixed portion

of the wrench when the latter is in engagement with the work.

2. A wrench comprising a slotted shank, a movable jaw slidable thereon, a rack positioned within the slot of said shank and having said jaw connected to the top thereof, a pinion journaled in said shank in mesh with said rack, said movable jaw having its engaging face partially cut-away, having a perforation therethrough and also having a recess therein, a face plate positioned in said cut-away portion and pivoted to said jaw, a dog pivoted in said recess to said jaw and a pin extending through said perforation, and resilient means normally depressing the pointed end of said dog, said dog adapted for automatic engagement with said shank upon an engagement of said pivoted plate with the work to be operated upon.

3. In combination with a toothed wrench shank having a longitudinal slot therein, of a movable rack within said slot, a slidable jaw pivoted to the upper end of said rack, said slidable jaw having a portion of its engaging face cut-away and having a recess with a perforation between said recess and cut-away portion, a face-plate pivoted to said jaw and positioned in said cut-away portion, a dog pivoted upon trunnions in parallelism with the axial pivot of said face plate and a pin extending through said perforation and adapted for engaging the adjacent surface of said plate, and resilient means socketed in said jaw normally maintaining said pin in contact with said plates, one end of said dog being pointed and adapted for locking engagement with the wrench proper upon a seating of the work upon said pivoted plate.

In testimony whereof I affix my signature in presence of two witnesses.

FERDINÁND DEÁK.
